UNITED STATES PATENT OFFICE.

ARCHIE E. LADEWIG, OF WAUKESHA, WISCONSIN, ASSIGNOR, BY MESNE ASSIGNMENTS, TO THE CREAMERY PACKAGE MFG. COMPANY, OF CHICAGO, ILLINOIS, A CORPORATION OF ILLINOIS.

BOTTLE-WASHING MACHINE.

Application filed October 26, 1922, Serial No. 596,931. Renewed October 15, 1926.

This invention relates in general to improvements in the art of automatically cleansing objects in succession, and relates more specifically to improvements in the construction and operation of machines for automatically washing bottles and the like with fluid.

An object of the invention is to provide a simple, compact and efficient machine for automatically and thoroughly cleansing bottles and the like in succession.

Some of the more important specific objects of the present invention are as follows:—

- 15 To provide a relatively simple and efficient bottle washer which will effectively clean bottles of various shapes and sizes.
- 20 To provide an extremely compact bottle washing machine having enormous capacity.
- 25 To provide improved mechanism for transporting bottles through a cleansing machine and for manipulating the bottles therein, without breaking or otherwise damaging the bottles.
- 30 To provide simple and effective means for automatically washing both the interiors and exteriors of a succession of bottles.
- 35 To provide improved driving and manipulating mechanism for bottle washing machines.

To provide improved bottle washing mechanism which may be readily assembled and dismantled, and the various elements of which are readily accessible for inspection, adjustment and cleaning.

To provide various other improvements in the construction and operation of bottle washing machines, whereby the cost of manufacture is reduced to a minimum and the efficiency is enhanced to a maximum.

A clear conception of an embodiment of the present invention and of the operation of machines constructed in accordance therewith, may be had by referring to the drawings accompanying and forming a part of this specification, in which like reference characters designate the same or similar parts in the several views.

Fig. 1 is a front elevation of an improved bottle washing machine, a portion of the structure having been broken away in order to more clearly illustrate details of construction of the mechanism.

Fig. 2 is a fragmentary side view of the

improved bottle manipulating mechanism, 55 showing one bottle which has just been inverted preparatory to interior cleansing thereof, and showing a finally washed bottle being discharged from the machine.

Fig. 3 is a side elevation of the improved bottle washing machine, showing an inverted bottle being subjected to internal cleansing thereof.

Fig. 4 is a fragmentary side view of the improved bottle manipulating mechanism, 65 showing one bottle being inverted, and showing a clean bottle being delivered from the inverted bottle holder to the reversing and final discharge shoe.

The improved bottle washing machine 70 comprises in general, mechanism for urging bottles of various shapes and sizes in succession through the machine, other mechanism for automatically and thoroughly washing the exteriors of the successive bottles during 75 their passage through the machine, and other mechanism for automatically and effectively cleansing the interiors of the successive bottles as they are being transported through the washer. These various mechanisms are supported by and substantially housed within a combined main frame and casing 2, and are driven by means of power derived from any suitable source, applied to a main horizontal actuating shaft 17 mounted in bearings supported by the casing 85 2.

The bottle transporting and manipulating mechanism comprises a longitudinally movable horizontal endless conveyer 3 adapted to receive the unwashed bottles 11 and to 90 urge them past the bottle exterior washing device, a transversely movable horizontal endless conveyer 4 cooperable with the conveyer 3 to manipulate the bottles 11 during external cleaning, a transverse series of tilt- 95 able bottle inverting chutes 6 adapted to receive the partially washed bottles 11 from the conveyer 3, a transverse series of tilttable bottle holders 7 adapted to receive the inverted bottles 11 from the chutes 6, a trans- 100 verse series of stationary inclined guides 12 for receiving the washed bottles 11 from the holders 7, and a transverse series of movable bottle righting shoes 9 adapted to receive the clean bottles 11 from the guides 12 and 105 to deliver them in upright position upon a final receiving table 10. The endless conveyor 3 is operable to urge the successive

bottles 11 forward beneath the exterior washing device, the conveyor 3 comprising a series of parallel horizontal transverse angle bars forming flights secured to and movable 5 by endless bands, between stationary parallel confining walls 62 extending longitudinally of the stretches of the endless bands. The moving flights on the endless bands are adapted to advance the bottles 11, neck foremost, toward and beneath the revolving scrubbing brush 5 and from thence toward the inverting chutes 6. The conveyor 4 automatically functions to rotate the bottles 11 about their own longitudinal axes during 10 their advancement past the brush 5.

The tilttable bottle inverting chutes 6 are pivotally supported upon a transverse pivot shaft 35 in longitudinal alinement with the 15 passages between the guide walls of the conveyor 3, and are swingable about the axis of the shaft 35 by means of a bell crank 33. The inverting chutes 6 are formed by a common base to which is secured a series of parallel upright walls 60 the lower ends 61 20 of which are bent laterally to engage and check the downward movement of the bottles 11 along the base. One arm of the bell crank 33 is pivotally connected with an end of the chute actuating lever 29 by means of 25 a link 32, while the other bell crank arm is pivotally connected with an elongated connecting member 23. The chute actuating lever 29 has its medial portion pivotally 30 associated with a shaft 37 mounted in the stationary casing 2, and has its rear end provided with a roller cooperable with a chute 35 tilting cam 30 carried by a revolving transverse cam shaft 15 supported in bearings in the casing 2.

The revoluble or tilttable bottle holders 7 are pivotally supported upon a transverse pivot bar 36 with their axes movable in the longitudinal paths of travel of the bottles 11, and are oscillatable about the axis of the bar 45 by means of an arm 31. The swinging extremity of the arm 31 carries a roller 34 which engages a slot formed in the forward swinging extremity of the holder operating lever 13. The medial portion of the lever 13 50 is pivoted upon the shaft 37 while the rear swinging end of the lever is provided with a roller cooperable with a holder tilting cam 28 carried by the revolving cam shaft 15.

The stationary inclined guides 12 are 55 located in the planes of travel of the advancing bottles 11 below the holders 7 and are adapted to direct the bottles upon the righting shoes 9. The shoes 9 are carried by swingable arms 22 carried by a pivot 24 which is 60 movable by means of an arm 27. The swinging extremity of the arm 27 is pivotally connected with the lower extremity of the connecting member 23 the upper extremity of 65 which is associated with the bell crank 33 as previously described. While the final receiv-

ing element has been illustrated as being a stationary table 10, it will be obvious that the clean bottles may be delivered to a conveyor or any other form of receiver.

From the foregoing description of the bottle transporting and manipulating mechanism, it will be obvious that this mechanism is automatically operable from the revolving cam shaft 15. The actuating power is delivered to the cam shaft 15 from the main power shaft 17 through a worm 16 coaxing with the worm wheel 14 secured to one end of the cam shaft 15. The worm gearing thus provided causes a considerable reduction in speed between the shafts 17, 15, with the result that the cams 28, 30 revolve slowly and periodically perform their intended functions.

The mechanism for automatically washing the bottle exteriors, as the bottles 11 are transported in series by the conveyor 3, comprises a rapidly revolving cylindrical scrubbing brush 5 extending transversely across the top of the machine in a well known manner. The brush 5 is driven from the main drive shaft 17 through bevel gearing 25 and a chain drive 26, shown in Fig. 3. The periphery of the rapidly revolving brush 5 is engageable with all portions of the bottles 11 as they are moved longitudinally beneath the brush by the conveyor 3 and are simultaneously rotated about their own axes by the conveyor 4.

The mechanism for automatically cleansing the interiors of the inverted bottles 11 while positioned in the holders 7, comprises a series of vertically reciprocable spray nozzles 8, and mechanism 20 for automatically delivering cleansing fluid to the interiors of the inverted bottles through the nozzles 8. This automatic bottle interior cleansing mechanism is of well known construction as shown in Patent No. 1,182,597, granted May 9, 1916, and forms no part of the present invention except in combination with the bottle manipulating mechanism. The nozzles 8 are guided for vertical and simultaneous reciprocation, by means of a carrier 21 slidably supported in stationary vertical guides on the casing 2, and are periodically upwardly and downwardly movable by means of an actuating lever 18 supported by a pivot shaft 19 and connected with the carrier by means of a link. The admission of cleansing fluid which is automatically delivered through the upper perforated extremities of the nozzles 8 as they advance upwardly into the inverted bottles 11, is controlled in a well known manner which it is unnecessary to describe specifically herein.

During normal operation of the improved bottle washing machine, the various transporting, manipulating and washing mechanisms are properly adjusted and set

in motion by means of power applied to the main driving shaft 17. The unwashed bottles are then delivered in horizontal position and in succession to the transporting 5 conveyer 3, the successive bottles being urged forward between the walls 62 toward the rapidly revolving brush 5. As the horizontally disposed bottles 11 engage the transverse conveyer 4 they are spun about 10 their own axes thereby permitting the brush 5 to thoroughly scrub the exterior surfaces of the advancing bottles. The partially washed bottles 11 are eventually delivered in succession over the forward end of the 15 conveyer 3 and upon the inclined inverting chutes 6 down which they slide and assume positions between the walls 60, and upon the lower ends 61 thereof, as indicated in Fig. 4. When the bottles have been 20 thus positioned in the chutes 6, the revolving cam 30 automatically engages the rear roller bearing end of the lever 29 and tilts the chutes 6 about the pivot shaft 37 to vertical positions as indicated in Fig. 2. 25 During forward tilting of the chutes 6, the bottles 11 are automatically dropped in inverted position into the adjacent holders 7, while the nozzles 8 are withdrawn, after which the empty chutes 6 are automatically 30 returned to normal inclined position preparatory to receiving subsequent bottles 11 delivered from the conveyer 3.

After the bottles 11 have been inverted and positioned in the holders 7 as shown 35 in Fig. 3, the nozzles 8 are automatically elevated through the holders 7 and through the necks of the bottles and cleansing fluid is simultaneously automatically delivered against all portions of the interiors of the 40 bottles to thoroughly wash and rinse the internal bottle surfaces. The nozzles 8 are preferably moved upwardly a fixed distance, and if the bottles 11 being washed, are relatively short, the nozzles 8 automatically lift 45 the bottles upwardly away from their supports during internal washing. After thorough injection of cleansing fluid, the nozzles 8 are automatically retracted causing the bottles 11 to again rest within the 50 holders 7. When the nozzles 8 have been completely withdrawn from the bottles and the 55 holders 7, and the cleansing fluid has drained from the washed bottles, the revolving cam 28 becomes effective by virtue of engagement with the lever 13 as indicated in Fig. 4, to tilt or revolve the holders 7 about the axis of the pivot bar 36. Upon sufficient tilting of the holders 7, the clean 60 bottles 11 eventually slide downwardly over the stationary guides 12 and upon the shoes 9 as illustrated in Fig. 4, the bottoms of the bottles resting against the curved rear edge of the receiving table 10. The empty 65 bottle holders 7 are subsequently automatically returned to normal vertical position

preparatory to receiving subsequent bottles 11 from the chutes 6. As the chutes 6 are tilted forward as indicated in Fig. 2, the bell crank 33 simultaneously functions by virtue of the member 23, arm 27 and carrier arms 22 to tilt the shoes 9 forward and to set the washed bottles in upright position upon the table 10. The shoes 9 are subsequently automatically returned to normal bottle receiving position, by the return motion of the chutes 6 to like position. In this manner the successive bottles 11 are automatically and gently conducted through the washer and are effectively cleaned during normal operation of the various mechanisms. 70

While the construction and operation of various mechanisms for actuating the bottle transporting and manipulating devices have been described in detail, it will be obvious that these mechanisms are capable of considerable modification in structure without departing from the scope of the present invention. The improved machine is capable of effectively cleaning bottles of various shapes and sizes, and the bottles 11 being simultaneously treated need not be of uniform shape or size. The machine is extremely compact when compared with prior devices of similar capacity, and is entirely automatic in its operation. The various elements of the structure are relatively simple, readily adjustable to effectively perform their functions, and conveniently accessible for cleaning or removal. The successive bottles which are ordinarily constructed of glass or other extremely brittle material, are gently conducted from place to place through the machine, without danger of breakage or other damage. The improved machine may be manufactured at relatively 85 low cost and is operable with minimum power and attendance. 90

It should be understood that it is not desired to limit the invention to the exact details of construction and of operation of the mechanism herein shown and described, for various modifications within the scope of the claims may occur to persons skilled in the art. 105

It is claimed and desired to secure by Letters Patent:—

1. In combination, a holder formed to support a bottle in inverted position, means for transporting a bottle resting upon its side and with its neck foremost toward the upper end of said holder, a tiltable chute formed to receive the bottle from said transporting means and to deliver the same in inverted position to said holder, a cleansing element movable upwardly into the bottle while supported by said holder, means for revolving said holder in one direction to discharge the cleansed bottle and in the opposite direction to return said holder to bottle receiving position. 110

tion, and a tiltable shoe for subsequently completely righting the cleansed bottle.

2. In combination, a holder formed to support a bottle in inverted position, means for transporting a bottle resting upon its side and with its neck foremost toward the upper end of said holder, a tiltable chute formed to receive the bottle from said transporting means and to deliver the same in inverted position to said holder, a cleansing element movable upwardly into the bottle while supported by said holder, and means for revolving said holder in one direction to discharge the cleansed bottle and in the opposite direction to return said holder to bottle receiving position.

3. In combination, means for holding a bottle in inverted position, means for transporting a bottle toward said holding means, means for setting a bottle delivered by said transporting means in said holding means in inverted position, means for cleansing the bottle while supported in said holding means and means for swinging said holding means in one direction to discharge a bottle therefrom and in the opposite direction to return said holding means to bottle receiving position.

4. In combination, a bottle holder formed to support a bottle in inverted position, means for transporting a bottle toward said holder, a chute for setting a bottle delivered by said transporting means in said holder in inverted position, means for cleansing the bottle while supported in said holder and means for swinging said holder in one direction to discharge a bottle therefrom and in the opposite direction to return said holder to bottle receiving position.

40 5. In combination, a bottle holder swingable in opposite directions about an axis, means for transporting bottles in succession toward said holder, means for receiving the successive bottles from said transporting means and for delivering said bottles to said holder in inverted position, means for cleansing the bottles while supported in said holder, and means for swinging said holder in one direction to discharge a bottle therefrom and in the opposite direction to return said holder to bottle receiving position.

6. In combination, a bottle holder tiltable in one direction to discharge bottles therefrom and swingable in the opposite direction to return said holder to normal bottle receiving position, means for transporting

bottles in succession toward said holder, a tiltable chute for receiving the successive bottles from said transporting means and for delivering said bottles to said holder in inverted position, and means for cleansing the successive bottles while supported in said holder.

7. In combination, transporting means formed to convey bottles in succession toward a common point of discharge, a tiltable bottle holder stationed below the discharge end of said transporting means, a tiltable chute for receiving the successive bottles from said transporting means and for delivering said bottles to said holder in inverted position, and means for cleansing the bottles while supported in said holder.

8. In combination, bottle transporting means, means for externally washing bottles while being conveyed by said transporting means, a tiltable holder stationed below the discharge end of said transporting means, a tiltable chute for setting bottles discharged by said transporting means in said holder in inverted position, and means for internally cleansing the bottles while supported in said holder.

9. In combination, bottle transporting means, means for externally washing the successive bottles being conveyed by said transporting means, a bottle holder stationed below the discharge end of said transporting means, means for receiving the bottles discharged by said transporting means and for placing said bottles in succession in said holder in inverted position, means for internally cleansing the successive bottles supported by said holder, and means for moving said holder in one direction to discharge the successive bottles therefrom and in the opposite direction to return said holder to bottle receiving position.

10. In combination, bottle transporting means, means for externally washing bottles while being conveyed by said transporting means, a bottle holder swingable about a horizontal axis and stationed below the discharge end of said transporting means, a chute tiltable about a horizontal axis to set the bottles discharged by said transporting means in said holder in inverted position, and means for internally cleansing the bottles while supported in said holder.

In testimony whereof, the signature of the inventor is affixed hereto.

ARCHIE E. LADEWIG.
